UNITED STATES PATENT OFFICE.

GEORGE E. HACKETT, OF ROSELLE, NEW JERSEY.

TWIST-DRILL.

No. 893,162.

Specification of Letters Patent.

Patented July 14, 1908.

Application filed October 6, 1906. Serial No. 337,811.

To all whom it may concern:

Be it known that I, GEORGE E. HACKETT, a citizen of the United States, residing at Roselle, in the county of Union and State of New Jersey, have invented certain new and useful Improvements in Twist-Drills, of which the following is a specification.

My invention has for its object to provide a form of twist drill of reduced cost and which may be manufactured from high speed steel, the difficulty of working which has heretofore limited its extensive use on account of the expense attending its manufacture by the methods now commonly employed. The drill as a whole is formed from a flat blank of proper size or shape, which may be fluted or channeled if desired, and which is twisted, both to form the spiral twist for the cutting body and also to form a shank, the curved exterior surface formed by the spiral twist of the shank being suitably shaped, either tapered or cylindrical as it may be desired; and my invention also consists in a drill having its shank so formed by twisting a blank. As preferably made, the shank is tapered to fit a standard twist-drill socket, but with saving of metal by reason of the skeletonized character of the shank portion.

In the accompanying drawings, Figure 1, is a side elevation of a drill made in accordance with this invention by the process herein described. Fig. 2, is an elevation of the point thereof, and Fig. 3, is an elevation of the shank.

In carrying out my invention, I take a suitable blank of suitable shape and twist the same, the pitch of the twist being determined by the material upon which the drill is to be used and by other factors well understood in drill designing. It is obvious that the pitch may be varied from point to point along the length of the drill as may be desired. Thus I preferably in designing my drill vary the pitch of the twist of the body in proportion to the bending moment at the corresponding points of the drill whereby increased strength is obtained, as by decreasing the pitch the spirals are brought more into parallelism with the force tending to prevent rotation of the drill, or to untwist it and more points of contact are provided between the shank and socket. Not only is the body part of the drill made by twisting the blank, but the shank is also made by twisting, thereby much reducing

the cost of manufacture over drills whose shanks are made by turning, grinding or rolling.

It is obvious that the taper of the shank may be obtained by a uniform twist of a proper blank, the shank forming end of which is a trapezoid, or by a uniform twist of a blank whose shank forming end is a rectangle and by subsequent grinding, but to cheapen construction I prefer to make the drill including the body and shank of a single rectangular blank, and to provide for variation of diameters along the drill and shank by a variation of the pitch of the twist; for by decreasing the pitch, that is by increasing the number of turns per unit of length, the diameter of the spiral produced by the twisting will be reduced. This is illustrated in Fig. 1 of the drawing in which the drill has been formed from a rectangular blank and the taper of the shank produced by a uniform variation of the twist along its length. Obviously these variations of diameter by a variation of the pitch of the twist may also take place if desired along the body portion of the drill. In this way the drill as produced by the twisting may be caused to approximately correspond to its desired finished diameter whereby the amount of grinding necessary to complete it may be greatly reduced if the drill, after twisting, is to have its surface accurately shaped by grinding. The tip of the shank is preferably left untwisted so as to provide the usual tang with sides parallel to the axis of the drill. It is further obvious that the point of the drill may be so formed by grinding or forging, or otherwise as will adapt it to the material to be operated on and that the blank itself may be channeled or grooved if desired to produce a corresponding cross section of the groove of the finished drill and that the drill, including shank and body, may be finished by grinding in any desired manner, my improved process contemplating the making of a drill from a suitable blank by twisting it in the manner before described and a variation of the pitch of the twist to cause the drill produced by such twisting to have at various points different diameters, whereby the amount of grinding, if any be necessary to finish the drill, is reduced.

While the drill shown in the accompanying drawings is adapted for use on metal, it is obvious that by proper designing drills may be produced by the process herein de-

scribed suitable for other and diverse materials. It will also be seen that when the drill is made in the manner described from a forged blank, the fibers of such blank are not severed or disconnected in the process of making the drill, but remain continuous therein, and that the diameter of the drill, either in the body or shank, may be varied without severing the fibers at the points of reduction.

Having thus described my invention what

I claim and desire to secure by Letters Patent is:

As a new and improved article of manufacture the herein described drill having a 15 twisted body portion and a twisted tapered shank, the shank having a twist of increasing pitch.

GEORGE E. HACKETT.
